Primary Examiner — Sandra Snapp(74) *Attorney, Agent, or Firm* — J.A. Lindeman & Co., PLLC(57) **CLAIM**

The ornamental design for a massage therapy device, as shown and described.

DESCRIPTION

FIG. 1 is a perspective view of our massage therapy device; FIG. 2 is a front view of the massage therapy device of FIG. 1;

FIG. 3 is a back view of the massage therapy device of FIG. 1; FIG. 4 is a right side view (the left side view being a mirror image) of the massage therapy device of FIG. 1;

FIG. 5 is a top view of the massage therapy device of FIG. 1; and,

FIG. 6 is a bottom view of the massage therapy device of FIG. 1.

The article is shown with a symbolic break in its length. The appearance of any portion of the article between the break lines forms no part of the claimed design.

1 Claim, 2 Drawing Sheets(56)
